UNITED STATES PATENT OFFICE.

AMOS H. SMITH, OF BROOKLYN, NEW YORK, ASSIGNOR TO AMERICAN BANK NOTE COMPANY, OF NEW YORK, N. Y., A CORPORATION OF NEW YORK.

NUMBERING HEAD.

Application filed August 10, 1921, Serial No. 491,663. Renewed February 17, 1923.

To all whom it may concern:

Be it known that I, AMOS H. SMITH, a citizen of the United States, residing at the borough of Brooklyn, in the city of New York, county of Kings, and State of New York, have invented certain new and useful Improvements in Numbering Heads, of which the following is a specification, reference being had therein to the accompanying drawings, which form a part thereof.

My invention relates to numbering heads, and more particularly to a type thereof wherein the digit wheels to be progressively actuated, will have associated therewith a mechanism which will ensure the timely actuation of wheels of progressively higher denomination, while avoiding likelihood of one wheel imparting a turning movement to the adjoining wheel of higher denomination in a manner to disturb the proper alinement of the printing surfaces, or cause a premature rotary movement of a digit wheel of higher denomination.

Heretofore in this art it has been the common practice to produce numbering heads having a sequence of digit wheels rotatable about a common axis, each of the digit wheels having a recess in the ratchet wheel through which it is actuated, the actuating means being what is known as a comb pawl, the teeth of which are of successively shorter length so as to permit these teeth, with the continued actuation of the sheet to successively engage and turn the digit wheel with which they are respectively associated and ensure this turning movement only when all of the wheels of lower denomination have the digit 9 exposed in the printing position, said comb pawl being supported upon a rock frame which is actuated by a plunger mechanism after each impression interval of the head. To produce what is known as a positive lock, various expedients are employed by which each digit wheel will be held against rotation, except when positively actuated by the comb pawl.

The above type of numbering head is particularly adapted for the production of what is known as "type high" heads wherein the numbering heads are set upon the numbering machine in close juxtaposition.

A numbering head embodying my invention is particularly adapted for larger work

than the ordinary "type high" head, and is so constructed as not to require the ordinary 55 comb pawl and plunger actuating mechanism, thus ensuring a positive, more gradual turning movement of the digit wheels and permitting the production of the heads with less precision work than is possible with the 60 plunger actuated heads.

To ensure positive action of the various digit wheels, I utilize each wheel as a part of the actuating means for the wheel of next higher denomination, and employ a transfer 65 mechanism in part actuated from the main source of power and in part actuated by the digit wheel of lower denomination while operative upon the digit wheel of next higher denomination.

The transfer wheel operative upon the units digit wheel carries a spur gear meshing with a gear actuated by means of a star wheel, the various transfer wheels being entirely independent, one of the other.

Associated with the transfer mechanism is a locking mechanism operative upon each transfer wheel excepting that associated with the units wheel, means being provided whereby this locking mechanism will be set 80 at all times excepting when the transfer wheel associated therewith is in a position so that its next actuation will impart movement to the wheel of next higher denomination, at which moment the locking mechanism will be released as a result of the movement of the wheel of lower denomination.

In a numbering wheel embodying my invention, each of the digit wheels may be set entirely independently of the others, manually operative means for releasing the locking mechanism being provided to facilitate the setting of the head.

The digit wheels themselves are provided with the usual detent or alinement pawls, such being provided to correct any slight errors in alinement due to wear upon the co-acting parts, although the precision with which the transfer wheels and the actuating means therefor act, makes the use of 100 such detent pawls merely a precautionary measure.

Heretofore in this art, the use of a transfer mechanism including spur gears has been found impracticable because with the ordinary arrangement of spur gears and a se-

- quence of intermeshing gears, slight error may develop in the production of the gears so that in the wheels of higher denomination this error will be multiplied to an extent to destroy the alinement of the characters after the machine has been operated a great number of times, although perfect alinement is secured when starting the machine upon lower numbers.
10. In a numbering head embodying my invention, but a single pair of spur gears is employed, the transfer wheels acting directly upon the digit wheels as distinguished from a gear wheel carried thereby, so that
15. no gear train is present in the mechanism which when a machine has been operated thousands of times can develop multiplied error to a point where there will be a loss of alinement.
20. The invention consists primarily in a numbering head embodying therein a sequence of digit wheels each having a plurality of gear teeth thereon, the tops of said teeth being formed as a printing surface, and said wheels being independently rotatable about a common axis, and means for progressively actuating said digit wheels comprising a sequence of transfer wheels each independently mounted to rotate about
25. an axis counter to that of said digit wheels, one transfer wheel being associated with each digit wheel, and each transfer wheel having gear teeth thereon adapted to co-operate with the gear teeth upon the digit wheel with which it is associated, one of the teeth of each of said transfer wheels being laterally extended to engage the teeth of the digit wheel of next higher denomination, and means for actuating the transfer wheel associated with the digit wheel of lowest denomination; and in such other novel features of construction and combination of parts as are hereinafter set forth and described, and more particularly pointed out in the claims hereeto appended.
- Referring to the drawings,
- Fig. 1 is a plan view of a numbering head embodying my invention;
- Fig. 2 is a front view thereof in the direction of movement of the numbering head when in operation;
- Fig. 3 is a section of the line 3—3 of Fig. 2;
- Fig. 4 is a side elevation from the right of Fig. 2;
- Fig. 5 is a perspective view of one of the transfer wheels from one side thereof; and
- Fig. 6 is a similar view from the other side thereof.
50. Like numerals refer to like parts throughout the several views.
- In the embodiment of my invention shown in the drawings, the main frame of the machine is shown at 10, said frame being provided with a fixed shaft 11 upon which are

idly mounted in close juxtaposition, a sequence of independently rotatable digit wheels 12, 13, 14, 15, 16, 17, 18 and 19 each of which is identical in construction so as to require a detailed description of but one of these wheels, as the units wheel 12. The said digit wheel has about the periphery thereof a sequence of ten long gear teeth 20, the tops of said teeth being formed as a printing surface 21, said printing surface having successively the digits 0 to 9 thereon in cameo type. Upon one side of the digit wheel is a ratchet wheel 22 associated with which is a spring-pressed detent and alining pawl 23.

Each of the wheels 13 to 19 contains similar teeth 20 having similar characters 21 thereon and carries a similar ratchet wheel 22 having associated therewith a similar detent and alining pawl 23.

55. All of the digit wheels 12 to 19 have rotary movement about a common axis and are progressively actuated from a single actuating mechanism through the medium of a transfer mechanism which, in addition to imparting the desired rotative moment to the digit wheels, also serves as a locking means to prevent the accidental movement of a wheel of higher denomination by a wheel of lower denomination as a result of fouling of the numbering head through an accumulation of ink between the different digit wheels.

Also carried by the frame 10 is a shaft 24 counter to the shaft 11, which shaft 24 has idly mounted thereon a sequence of transfer wheels 25, 26, 27, 28, 29, 30, 31 and 32 associated and co-operating with the digit wheels 12 to 19 respectively. Each of the transfer wheels 26 to 32 is identical in construction and arrangement of parts with every other, with the exception that the wheels 26 and 27 are heavier in construction than the remaining wheels, to compensate for the increased wear to which they are subjected by reason of the greater frequency with which the wheels of lower denomination are actuated. The transfer wheel 25 is much heavier than the wheels 26 and 27.

By the employment of transfer wheels arranged in the manner described, great compactness is permitted to the structure of the numbering head while affording clearance sufficient to permit the utilization of heavy parts, as compared with those ordinarily employed in numbering heads.

60. While the transfer wheel 25 possesses all of the characteristics of the remaining transfer wheels, it also has structural characteristics by which it is operatively connected with the main actuating mechanism. Hence in describing in detail the transfer mechanism, the transfer wheel 25 associated with the units wheel 12 will be referred to, similar reference numerals being applied to cor-

responding parts in the other transfer wheels.

The wheel 25 has a sequence of ten gear teeth 33 spaced equally about the periphery thereof and adapted to co-operate with the teeth 20 upon its associated digit wheel 12, the recess between succeeding teeth 33 being of sufficient depth, and so formed, as to receive the printing surface 21 without rubbing contact therewith, so as to avoid abrasion of this surface or the transfer of ink therefrom to the transfer wheel. Upon one side of this wheel 25 is a ratchet wheel 34 permanently united therewith and upon the other side thereof also permanently united therewith is a release plate 35 having a trip tongue 36, the function of which will more fully appear hereinafter. Said transfer wheel 25 also has permanently secured thereto an ordinary spur gear wheel 37 by means of which the wheel is intermittently actuated by the actuating means which will be more fully referred to hereinafter.

Associated with the ratchet wheel 34 is a spring-pressed detent and alining pawl 38 which has no locking function with regard to the transfer wheel or its associated digit wheel, since this wheel is rotated one-tenth of a revolution with each actuation of the numbering head by a positively operative actuating mechanism which is always operatively connected therewith.

The transfer wheels 26 to 32 are identical in construction with the wheel 25 with the exception that they carry no gear wheel 37 and instead of being positively actuated directly by the actuating mechanism, are actuated by said mechanism through the medium of the digit wheels with which they are respectively associated.

Associated with each of the digit wheels 26 to 32 is a spring pressed locking pawl 39, which in addition to preventing any movement of the transfer wheel with which it is associated, and the digit wheel actuated thereby, except when the digit 9 upon the digit wheel of next lower denomination than said last named digit wheel is in the printing position, also acts as a detent and alining pawl with relation to the digit wheel associated with its transfer wheel. Said pawls 39 co-operate with the ratchet wheels 34 upon the respective transfer wheels, but are broader than said ratchet wheels so as to project in the plane of movement of the trip tongue 36, which is so set with relation to its digit wheel as to operatively engage said pawl when the digit 9 upon said wheel is in the printing position. The trip tongue adapted to be engaged by said pawl will, however, be carried by the digit wheel of lower denomination than that carrying the ratchet wheel with which said pawl is associated.

Each of the pawls 39 is provided with an

extending heel 40 adapted to be engaged by a flattened, or cam, shaft 41 extending transversely of the frame 10 and provided with an actuating handle 42 so that by the raising of said handle all of the pawls 39 may be simultaneously disengaged from their associated ratchet wheels, and thus permit a free rotation of the transfer wheel through the medium of its associated digit wheel in setting the head.

While I have referred to the transfer wheels 25 to 32 as being associated with a single digit wheel, this association relates merely to the continuous relation of the transfer wheel to a digit wheel, one of the teeth 33 of each of said transfer wheels having a lateral extension 33^a adapted to operatively engage the digit wheel of next higher denomination once during each full rotation of said transfer wheel, thus causing the transfer wheel associated with one digit wheel to impart a one-tenth rotation to the digit wheel of next higher denomination upon the actuation of the wheel of lower denomination following that which brings the digit 9 to the printing position. To secure this result, the various transfer wheels are staggered in relation to the digit wheels, there being normally clearance permitting the rotation of the transfer wheel at all times until the extension 33^a reaches the operative position with relation to the wheel adjoining that which rotates said transfer wheel.

Mounted in suitable bearings in the frame 10 is a shaft 43 carrying a spur gear 44 meshing with the gear 37, said shaft carrying thereon, externally of said frame, a five-arm star wheel 45 adapted to engage an abutment upon the frame of the numbering machine immediately following each impression, so as to set the numbering head preparatory to the making of the next impression. If desired a series of such abutments spaced apart may be employed to ensure the skipping of numbers by each numbering head during the printing operation, which is sometimes desirable where a plurality of numbering heads are arranged successively to print upon a sheet wherein a plurality of such numbers are required, and duplication of numbers upon succeeding sheets is to be avoided.

Since there are but five arms upon the star wheel 45 and since it is required to impart a one-tenth revolution upon each actuation of the star wheel to the transfer wheel co-operating with the units digit wheel, the diameter of the gear 44 will be one-half that of the gear 37.

To avoid any tendency of the gear 44 to overrun, I provide a stop mechanism consisting of a recessed hub 46 carried by the shaft 43 and star wheel 45, said hub having a recess 47 therein adjacent each arm of said star

wheel. Pivots mounted upon the side of the frame 10 is a swing arm 48 having an anti-friction roller 49 adapted to engage said hub and enter said recesses respectively so as to exert both a braking pressure and act as a limit stop. Acting upon said arm is a coiled spring 50.

The pawls 38 and 39 are mounted upon the shaft 51, the springs acting upon said pawls being tensioned by having one end thereof passed about the shaft 41. The pawls 23 are mounted upon the shaft 52, the springs acting thereon being tensioned by having one end thereof engaged with the shaft 53.

15 The operation of the herein described mechanism is substantially as follows:—

When it is desired to set the head when starting a run, the shaft 41 is turned by means of the handle 42 so as to rock each of the pawls 39 upon the shaft 51 until they are disengaged from their co-operating ratchet wheels 34, thus releasing each of the digit wheels above the units wheel and permitting it to be freely turned by hand entirely independently of the other digit wheels, the transfer wheel associated with each digit wheel turning therewith to preserve the proper relation of the transfer mechanism and the digit wheels, but having no function 25 in moving any of the digit wheels.

When the digit 9 of each wheel 12-19 has been brought into the printing position, the main actuating mechanism may be advanced one stage and throw all of the digit wheels 35 to the zero position. Of course if some definite number is to be set up, each of the wheels may be positioned with the digit forming a part of said number in the proper printing position. The shaft 41 is then reversed to 40 permit the setting of the pawls 39 so that thereafter the transfer wheels associated with said pawls will all be locked or held against movement under normal conditions, or until, as a result of the progressive actuation of the several digit wheels, movement of a particular digit wheel is required.

For purposes of making the operation of the head clear, it will be assumed that the starting number is 9333.

50 As the numbering head leaves the printing position, the fixed abutment upon the numbering machine (not shown) will engage one of the arms of the star wheel 45, and with the continued movement of the head, the shaft 43 carrying the gear wheel 44 and said star wheel 45, will receive a continuing uniform rotary movement amounting to one-fifth of a revolution thereof. Since the gear 44 is one-half the diameter of the gear 37, this latter gear wheel will receive one-tenth of a rotation.

The development of moving inertia in the actuating mechanism is prevented by the lever 48 and its wheel 49 as a result of the pres-

sure exerted thereby against the hub 46 under the spring 50. When the hub has turned one-fifth of a revolution, the wheel 49 will enter a recess 47 and check further movement of the star wheel and of the intermeshing gears 44 and 37, the transfer wheel 25 and 70 digit wheel 12.

With each actuation of the transfer wheel 25, the pawl 39 associated therewith will assist the stop mechanism acting upon the star wheel shaft in preventing overrunning of 75 parts and will also serve to impart any slight additional movement to said transfer wheel as may be necessary to secure the proper alignment of the printing character 21, the pawl 23 acting upon the units digit wheel 80 having the same effect with relation to the digit wheel proper as the pawl 39 with relation to its transfer wheel. In this manner any slight wear upon the gears 44 and 37 or the teeth of the transfer wheel or the digit 85 wheel will be automatically compensated for.

When the units wheel 12 has any digit except 9 in the printing position, the tens digit wheel 13 will be locked by the pawl 39 co-operating with the transfer wheel 26 associated with said tens digit wheel 13. Hence rotation of the units wheel cannot impart rotary movement to the tens wheel at such time. When the units digit wheel, however, is turned to bring the digit 9 in the printing 95 position, the tongue 36 will engage and raise the pawl 39 from its operative locking engagement with the ratchet wheel 34, the extension 33^a of one tooth 33 upon the transfer wheel 25 being at this moment engaged with 100 a tooth 29 upon the tens digit wheel 13 so that with the next actuation of the head, the units and the tens wheels will be simultaneously actuated through the same transfer wheel. This operation with the continued 105 actuation of the head, will follow progressively throughout the entire head, in the respect that when all digit wheels of a lower denomination have the digit 9 in the printing position, all of such wheels above the units 110 wheel and the wheel of next higher denomination will have the locking pawl 39 disengaged from its co-operating ratchet wheel 34 so that upon the next actuation of the head, all of these wheels of next higher denomination will be simultaneously turned one-tenth of a revolution.

Following the assumption that the starting number is 9333, when the head has been actuated six times, the locking pawl for the transfer wheel 26 will be made inoperative 120 so that upon the tenth revolution the head will register 9340, whereupon the locking pawl will again become operative as to the wheels 13 and 26.

While the digit wheel 15 has the digit 9 in the printing position, thus causing the tongue 36 carried by the transfer wheel 28

to release the locking pawl 39 associated with the transfer wheel 29, there is no danger of this released wheel being accidentally turned, since the transfer wheels 26, 27 and 5 28 will all be locked against movement, the relation of parts being such that a wheel of higher denomination cannot be turned except simultaneously with all wheels of lower denomination.

10 With the continued operation of the machine, the tens wheel 13 will be turned through the medium of the transfer wheel 25 one-tenth of a revolution with each ten revolutions of said transfer wheel 25, and 15 its associated digit wheel 12, the transfer wheel 26 associated with the digit wheel 13 receiving simultaneous and similar rotary movement as said digit wheel. Consequently with each tenth revolution of each digit 20 wheel and its associated transfer wheel, the wheel of next higher denomination will receive from the transfer wheel associated with the wheel of lower denomination, one-tenth of a revolution, which condition will 25 be carried progressively through the machine. Whenever the digit 9 of any wheel 12 to 19 is in the printing position, the locking mechanism operative upon the ratchet 30 34 of the transfer wheel associated with the digit wheel of next higher denomination will be released.

With a construction as described, the various digit wheels may be properly spaced or justified through the medium of the 35 ratchet wheels 22 which may be made fairly substantial while still having the digit wheels sufficiently close together. By utilizing the tops of gear teeth for forming the printing surface, substantial means for imparting rotary movement to the digit wheel is afforded, the form of the co-operating transfer wheel being such as to avoid injury to the printing surface. By using transfer wheels which are always directly geared to 40 their associated digit wheels, absolute uniformity in the functioning of the head as a whole is secured and the extended tenth tooth will ensure timely and accurate actuation of a digit wheel of higher denomination by the 45 transfer wheel associated with the digit wheel of next lower denomination.

The particular transfer mechanism employed also permits its utilization for locking the digit wheels above the units wheels 55 at all times except when any of said wheels is to be turned. By associating the locking mechanism with the transfer wheel, more substantial parts may be used. By providing transfer wheels with a locking ratchet 60 wheel upon one face thereof and a releasing disk upon the other face thereof, said disk upon a wheel of lower denomination will be presented adjacent the ratchet wheel of the transfer wheel of next higher denomination

so that both said ratchet wheel and said releasing disk may co-operate with a single pawl having no small parts thereon. 65

It is not my intention to limit the invention to the precise details of construction shown in the accompanying drawings, it 70 being apparent that such may be varied without departing from the spirit and scope of the invention.

Having described the invention, what I claim as new and desire to have protected 75 by Letters Patent, is:—

1. A numbering head embodying therein a sequence of digit wheels each having a plurality of gear teeth thereon, the tops of said teeth being formed as a printing surface, and said wheels being independently rotatable about a common axis, and means for progressively actuating said digit wheels comprising a sequence of transfer wheels 80 each independently mounted to rotate about an axis counter to that of said digit wheels, one transfer wheel being associated with each digit wheel, and each transfer wheel having gear teeth thereon adapted to co-operate with the gear teeth upon the digit 85 wheel with which it is associated, one of the teeth of each of said transfer wheels being laterally extended to engage the teeth of the digit wheel of next higher denomination, and means for actuating the transfer wheel 90 associated with the digit wheel of lowest 95 denomination.

2. A numbering head embodying therein a sequence of digit wheels each having a plurality of gear teeth thereon, the tops of said teeth being formed as a printing surface, and said wheels being independently rotatable about a common axis, means for progressively actuating said digit wheels comprising a sequence of transfer wheels 100 each independently mounted to rotate about an axis counter to that of said digit wheels, one transfer wheel being associated with each digit wheel, and each transfer wheel having gear teeth thereon adapted to co-operate with the gear teeth upon the digit 105 wheel with which it is associated, one of the teeth of each of said transfer wheels being laterally extended to engage the teeth of the digit wheel of next higher denomination, and means for actuating the transfer wheel 110 associated with the digit wheel of lowest 115 denomination.

The particular transfer mechanism employed also permits its utilization for locking the digit wheels above the units wheels 120 at all times except when any of said wheels is to be turned. By associating the locking mechanism with the transfer wheel, more substantial parts may be used. By providing transfer wheels with a locking ratchet wheel upon one face thereof and a releasing disk upon the other face thereof, said disk upon a wheel of lower denomination will be presented adjacent the ratchet wheel of the transfer wheel of next higher denomination when the extended tooth of the wheel carry-

ing said releasing means is in a position to operatively engage said last named digit wheel.

3. A numbering head embodying therein a sequence of digit wheels each having a plurality of gear teeth thereon, the tops of said teeth being formed as a printing surface, and said wheels being independently rotatable about a common axis, means for progressively actuating said digit wheels comprising a sequence of transfer wheels each independently mounted to rotate about an axis counter to that of said digit wheels, one transfer wheel being associated with each digit wheel, and each transfer wheel having gear teeth thereon adapted to co-operate with the gear teeth upon the digit wheel with which it is associated, one of the teeth of each of said transfer wheels being laterally extended to engage the teeth of the digit wheel of next higher denomination, and means for actuating the transfer wheel associated with the digit wheel of lowest denomination, a ratchet wheel carried by each of said transfer wheels, a locking pawl associated therewith, and a releasing tongue carried by each of said transfer wheels and adapted to operatively engage the locking pawl co-operating with the ratchet wheel of the adjacent transfer wheel, whereby said pawl will be disengaged from said ratchet wheel when the extended tooth of the wheel carrying said releasing tongue is in a position to operatively engage the digit wheel with which said adjacent transfer wheel meshes.

4. A numbering head embodying therein a sequence of digit wheels each having a plurality of gear teeth thereon, the tops of said teeth being formed as a printing surface, and said wheels being independently rotatable about a common axis, means for progressively actuating said digit wheels comprising a sequence of transfer wheels each independently mounted to rotate about an axis counter to that of said digit wheels, one transfer wheel being associated with each digit wheel, and each transfer wheel having gear teeth thereon adapted to co-operate with the gear teeth upon the digit wheel with which it is associated, one of the teeth of each of said transfer wheels being laterally extended to engage the teeth of the digit wheel of next higher denomination, and means for actuating the transfer wheel associated with the digit wheel of lowest denomination, locking means co-operating with each of said transfer wheels excepting the transfer wheel associated with the digit wheel of lowest denomination, whereby it is held against movement, and releasing means carried by each digit wheel of lower denomination operative upon said last named means to release said means and permit the

rotation of the transfer wheel with which it co-operates and its associated digit wheel when the extended tooth of the wheel carrying said releasing means is in a position to operatively engage said last named digit wheel, and means whereby said locking means may be manually released to permit the setting of any digit wheel.

5. A numbering head embodying therein a sequence of digit wheels each having a plurality of gear teeth thereon, the tops of said teeth being formed as a printing surface, and said wheels being independently rotatable about a common axis, means for progressively actuating said digit wheels comprising a sequence of transfer wheels each independently mounted to rotate about an axis counter to that of said digit wheels, one transfer wheel being associated with each digit wheel, and each transfer wheel having gear teeth thereon adapted to co-operate with the gear teeth upon the digit wheel with which it is associated, one of the teeth of each of said transfer wheels being laterally extended to engage the teeth of the digit wheel of next higher denomination, and means for actuating the transfer wheel associated with the digit wheel of lowest denomination, a ratchet wheel carried by each of said transfer wheels, a locking pawl associated therewith, a releasing tongue carried by each of said transfer wheels and adapted to operatively engage the locking pawl co-operating with the ratchet wheel of the adjacent transfer wheel, whereby said pawl will be disengaged from said ratchet wheel when the extended tooth of the wheel carrying said releasing tongue is in a position to operatively engage the digit wheel with which said adjacent transfer wheel meshes, each of said locking pawls having a heel, and a flattened or cam shaft rotatably mounted adjacent all of said heels and operative thereon, whereby said pawls may be manually released to permit the setting of any digit wheel.

6. A numbering head embodying therein a sequence of digit wheels each having a plurality of gear teeth thereon, the tops of said teeth being formed as a printing surface, and said wheels being independently rotatable about a common axis, and means for progressively actuating said digit wheels comprising a sequence of transfer wheels each independently mounted to rotate about an axis counter to that of said digit wheels, one transfer wheel being associated with each digit wheel, and each transfer wheel having gear teeth thereon adapted to co-operate with the gear teeth upon the digit wheel with which it is associated, said gear teeth being set apart to receive the teeth of the digit wheel with which it meshes, the space between said set apart teeth being

so formed as to avoid the engagement of the printing surface upon the digit wheel with the transfer wheel, one of the teeth of each of said transfer wheels being laterally extended

5 to engage the teeth of the digit wheel of next higher denomination, and means for actuating the transfer wheel associated with the digit wheel of lowest denomination.

7. A numbering head embodying therein 10 a sequence of digit wheels each having a plurality of gear teeth thereon, the tops of said teeth being formed as a printing surface, and said wheels being independently rotatable about a common axis, and means for 15 progressively actuating said digit wheels comprising a sequence of transfer wheels each independently mounted to rotate about an axis counter to that of said digit wheels, one transfer wheel being associated with 20 each digit wheel, and each transfer wheel having gear teeth thereon adapted to co-operate with the gear teeth upon the digit wheel with which it is associated, one of the teeth of each of said transfer wheels being 25 laterally extended to engage the teeth of the digit wheel of next higher denomination, and means for actuating the transfer wheel associated with the digit wheel of lowest denomination, comprising intermeshing spur 30 gears one of which is carried by the transfer wheel associated with the digit wheel of lowest denomination, and the other of which is carried by a shaft rotatably mounted adjacent said first named gear wheel, and a star 35 wheel carried by said shaft and adapted to be intermittently rotated.

8. A numbering head embodying therein 40 a sequence of digit wheels each having a plurality of gear teeth thereon, the tops of said teeth being formed as a printing surface, and said wheels being independently rotatable about a common axis, a ratchet wheel carried by each of said digit wheels, a detent and alining pawl co-operating with 45 each of said ratchet wheels, means for progressively actuating said digit wheels comprising a sequence of transfer wheels each independently mounted to rotate about an axis counter to that of said digit wheels, one 50 transfer wheel being associated with each digit wheel, and each transfer wheel having gear teeth thereon adapted to co-operate with the gear teeth upon the digit wheel with which it is associated, one of the teeth of each of said transfer wheels being laterally 55 extended to engage the teeth of the digit wheel of next higher denomination, and means for actuating the transfer wheel associated with the digit wheel of lowest denomination, a ratchet wheel carried by 60 each of said transfer wheels, a locking pawl associated therewith, and a releasing tongue carried by each of said transfer wheels and adapted to operatively engage the locking 65 pawl co-operating with the ratchet wheel of

the adjacent transfer wheel, whereby said pawl will be disengaged from said ratchet wheel when the extended tooth of the wheel carrying said releasing tongue is in a position to operatively engage the digit wheel 70 with which said adjacent transfer wheel meshes.

9. A numbering head embodying therein a sequence of digit wheels each having a plurality of gear teeth thereon, the tops 75 of said teeth being formed as a printing surface, and said wheels being independently rotatable about a common axis, and means for progressively actuating said digit wheels comprising a sequence of transfer 80 wheels each independently mounted to rotate about an axis counter to that of said digit wheels, one transfer wheel being associated with each digit wheel, and each transfer wheel having gear teeth thereon adapted 85 to co-operate with the gear teeth upon the digit wheel with which it is associated, one of the teeth of each of said transfer wheels being laterally extended to engage the teeth of the digit wheel of next higher denomination, and means for actuating the transfer wheel associated with the digit wheel of 90 lowest denomination, comprising intermeshing spur gears one of which is carried by the transfer wheel associated with the digit 95 wheel of lowest denomination, and the other of which is carried by a shaft rotatably mounted adjacent said first named gear wheel, and a star wheel carried by said shaft and adapted to be intermittently rotated, and means preventing over-running of 100 the shaft carrying said star wheel.

10. A numbering head embodying therein a sequence of digit wheels each having a plurality of gear teeth thereon, the tops of 105 said teeth being formed as a printing surface, and said wheels being independently rotatable about a common axis, and means for progressively actuating said digit wheels comprising a sequence of transfer wheels 110 each independently mounted to rotate about an axis counter to that of said digit wheels, one transfer wheel being associated with each digit wheel, and each transfer wheel having gear teeth thereon adapted to co-operate 115 with the gear teeth upon the digit wheel with which it is associated, one of the teeth of each of said transfer wheels being laterally extended to engage the teeth of the digit wheel of next higher denomination, and means for actuating the transfer wheel associated with the digit wheel of lowest 120 denomination, comprising intermeshing spur gears one of which is carried by the transfer wheel associated with the digit wheel of 125 lowest denomination, and the other of which is carried by a shaft rotatably mounted adjacent said first named gear wheel, and a star wheel carried by said shaft and adapted to be intermittently rotated, and means pre- 130

venting over-running of the shaft carrying said star wheel, comprising a hub having a recess adjacent each arm of said star wheel, a lever pivotally mounted adjacent said hub, an anti-friction roller carried by said lever and adapted to enter said recesses respectively, and a spring acting against said lever to force said roller against said hub.

In witness whereof I have hereunto affixed my signature, in the presence of two ¹⁰ scribing witnesses, this 3d day of August, 1921.

AMOS H. SMITH.
